STRAND OR ROPE MAKING MACHINE

Anton Kraft, Olpe, Germany

Application August 1, 1934, Serial No. 737,998
In Great Britain March 2, 1934

8 Claims. (Cl. 117—16)

This invention relates to strand or rope making machines of the kind in which the individual wires or strands which may have been provided with a backtwist are led to a flyer by the operation of which two twists in the like direction are imparted to the bundle of wires or strands in one revolution of the flyer.

In the construction of machines described in British Specification No. 365,793 the individual wires or strands are led together through the stub journal of the flyer and then in an outward direction from the axis of rotation of the flyer to a separating plate secured to one end of a shaft rotatably mounted in the flyer and then generally parallel with the shaft to a second separating plate from which the wires or strands are led in a bundle to a guide pulley of relatively small diameter and then in an inward direction toward the axis of the flyer over a second guide pulley to a hollow shaft extending through a stub journal of the winding frame which is floatingly mounted in the flyer.

According to the present invention the flyer is constructed to lead the wires or strands as a bundle in a forward direction lengthwise of the flyer to a point remote from the axis thereof and, for returning the bundle of wires or strands towards the axis of the flyer and thence, for instance, to winding mechanism associated therewith, is provided with guiding means adapted to permit substantially free twisting motion of the portion of the bundle of wires or strands which is in contact with it.

In other words, in accordance with the invention the guiding means is adapted to provide a minimum of resistance to the travel of the bundle of wires or strands towards the winding mechanism and to the rotation of the bundle of wires or strands about its own axis.

Thus, in accordance with the invention, the guiding means may comprise a combination of rolling bodies, such as balls or rollers arranged to oppose the minimum of resistance to the twisting of the bundle of wires or strands as it passes over them.

The guiding means in question is preferably so formed or arranged that the bundle of wires or strands in its travel toward the winding mechanism is subjected to a gradual change of direction.

Thus, the guiding means in question is adapted to cause the bundle of wires or strands in its travel from the point remote from the axis of rotation of the flyer towards the said axis to be

bent through a cuved or curves of relatively large radius.

The guiding means may in effect constitute a pulley the greater proportion of the surfaces of which adapted to contact with the rope consists of bodies free to rotate about axes at right-angles to the axis of rotation of the pulley.

For instance, the pulley may comprise a plurality of rollers arranged to rotate about axes at right-angles to the axis of rotation of the pulley and forming in effect the base of the groove therein and a plurality of rollers located upon the portions of the pulley constituting the flanges thereof.

In some cases, it may be found convenient to provide the pulley with two sets of rollers arranged concentrically one on each side of the body of the pulley, the rollers of the one set being staggered relatively to the rollers of the other in such manner that the alternating rollers of the two sets overlap slightly inward thus providing in effect a groove in which the bundle of wires or strands will travel.

The guiding means may be in the form of a pulley of the character defined above of a diameter equal to the distance between the axis of rotation of the flyer and the farthest point from the said axis reached by the bundle of wires or strands in its passage from one end to the opposite end of the flyer; thus when the bundle of wires or strands is led from adjacent to one end of the flyer towards the opposite end of the flyer in a path parallel with the axis of the flyer, the diameter of the pulley functioning as guiding means will be equal to the distance between the axis of the flyer and the general line of travel of the bundle of wires or strands in the direction in question.

The particular constructions of guiding means above described in detail are given by way of example for, as will be appreciated, rolling bodies may be associated with suitable supports in a variety of manners to provide a guide which will afford substantially no resistance to the travel of the bundle of wires or strands while permitting substantially free twisting motion of the portion of the bundle of wires or strands in contact with them.

The invention will be described further in detail and by way of example with reference to the accompanying drawings, in which:—

Figure 1 illustrates a general arrangement of a strand or rope making machine in accordance with the invention.

ing the wires or strands in order to provide them with a backtwist before they are brought together and treated by the machine illustrated in Figure 1, and

5 Figures 3, 4, 5 and 6 are fragmentary views of guiding means embodied in a strand or rope making machine in accordance with the invention.

10 As shown in Figure 1, the flyer is formed of a plurality of longitudinally arranged members 1 secured to an end member 2 and a further end member 3, the latter being provided with a trunnion 4 rotatably mounted in bearings 5 and furnished with a sprocket 6 by which the flyer will 15 be rotated.

15 In addition, the flyer is provided with intermediate members 7 and 8 forming rolling rings bearing on rollers 9 and 10, while the end member 2 is arranged to form a rolling ring bearing 20 on rollers 11.

20 The winding frame, of which the body is indicated by the reference 12, is furnished at one end with a hollow stub shaft 13 journaled in a bearing 14 in the member 8 and at the other end with a stub shaft 15 journaled in a bearing 25 16 in the end member 2 in such manner that notwithstanding the rotation of the flyer as a whole the winding frame will retain substantially the position shown in the drawings.

25 30 Between the members 3 and 8 there extend a pair of longitudinal members 17, of which only one can be seen, which form a support for the axle 18 of the guide pulley 19, the construction of which will be described hereafter, 20 being a counterweight adapted to balance, when the flyer is rotated, the overhung weight of the guide pulley 19.

30 35 On the hollow shaft 13 there is mounted a worm 21 engaging a worm wheel 22 secured to 40 a shaft 23 journaled in the body 12 of the winding frame and on the shaft 23 is arranged also a spur wheel 24 in engagement with the spur wheel 25 on the shaft 26 also journaled in the body 12 of the winding frame and on this shaft 45 there is provided a pinion 27 meshing with the spur wheel 28 on the shaft 29 on which is also mounted a sprocket 30 driving through the chain 31 a sprocket 32 provided on the spindle 33 on which is removably mounted a drum 34 on to 50 which the finished rope or strand is wound in the operation of the machine.

50 55 On the spindle 33 there is also mounted a pinion 35 driving through the spur wheel 36 a spur wheel 37 mounted on the shaft 38 which serves to impart appropriate traversing motion to the guide forks 39 by which the turns of the rope are appropriately positioned on the drum. On the end member 2 there is provided a bracket 40 supporting the spindle 41 of the guide pulley 60 42 over which the bundle of wires or strands are led from the die 43 which is arranged to be rotated from the shaft 45 through the intermediary of a chain drive indicated by the reference 46.

60 65 This guide pulley is of a construction similar to that of the pulley 19 that is to say it is of a character adapted to permit substantially free rotation of the bundle of wire elements as well as the forward or axial travel thereof.

70 75 Referring to Figure 2, 47 are the end members of a frame in which are rotatably mounted a plurality of flyers 49, each of which is provided with a floating carriage 50 in which a spool 51 of stranded wire or wire to be laid up in the form of rope or strands, as the case may be, is arranged.

From each of the spools the wire or strand is withdrawn, being led below a grooved pulley 52 and about the grooved pulley 53, thence over the pulley 54, which is also grooved, and finally over the pulley 55 through the hollow spindle 56 which is journaled in one of the end members 47, a corresponding spindle 57 being provided at the opposite end of the flyer journaled in a bearing in the other member 47.

10 To the last-mentioned spindle there is keyed a 10 spur wheel 58 engaging a toothed wheel 59 engaging a pinion on the shaft 45 and by the rotation of the toothed wheel in question each of the flyers is rotated in a direction giving a backtwist to the individual wires or strands. 15

15 The material forming the core of the rope, which may be stranded vegetable fibre, is twisted by the operation of the flyer 60 in which is floatingly arranged the cradle 61 forming a support for a spool 62 of the core material. This flyer is 20 provided with stub shafts 63 and 64 engaged in bearings 65, 66 and one of the stub shafts is furnished with a sprocket 67 in driving connection with a sprocket 68 mounted upon the shaft 45 which is driven by the motor 69. 25

20 The core material is drawn off the spool and led below the grooved pulley 70 about the pulley 71, over the pulley 72, then over the pulley 73 and thence through the hollow trunnion or stub shaft 63. 30

30 At this point the general operation of the machine may be described before considering in detail the construction of the guide pulley 19.

30 35 The core material, which is twisted by the operation of the flyer 60, and its associated parts, and the individual strands or wires drawn from the several spools 54 mounted in the flyers 51, by which a backtwist is imparted to them, are taken through the laying plate 44 and through the die 43 as a bundle, over the guide pulley 42, 40 thence along the flyer shown in Figure 1, over the guide pulley 19, through the hollow spindle 21 and to the drum 34 mounted in the winding mechanism.

35 40 The flyer shown in Figure 1, being maintained 45 in rotation, will cause the bundle of strands or wires to be given a double twist in its passage from the die 43 to the point at which it passes through the hollow stub shaft 13. In order that this double twist may satisfactorily be imparted 50 to the bundle of strands or wires, as the case may be, the guide pulley 19 is arranged to permit not only a free motion of the bundle in an axial direction but also substantially free rotational motion of the bundle. 55

40 45 To this end the guide pulleys 19 and 42 are each provided with a plurality of anti-friction bodies adapted to permit such rotational motion. Certain arrangements of these anti-friction bodies are illustrated by way of example in Figures 60 3 to 6.

45 50 In Figures 3 to 5 the anti-friction bodies are rollers, of which, in the case of the construction illustrated in Figures 3 and 4, there are provided three sets pivotally mounted in transverse members 74 connecting the side members 75 of the pulley, 76 representing the spindle of a roller 77 forming the base of the groove in which the bundle of wires or strands will be guided, while 78 and 79 represent the spindles of the rollers 70 75 80, 81 forming the side walls of the groove, the rollers forming the base of the groove alternating with rollers forming the side guides or members, as may be seen from Figure 3.

50 55 In the case of the construction shown in Figure 75

5, the side members 75 of the pulley are connected together by transverse members 74, as in the preceding construction, and in these transverse members there are rotatably engaged the 5 spindles 82 of the rollers 83.

These rollers are arranged in staggered relationship and their surfaces form in effect the side walls and also the base of the groove in which the bundle of wires runs.

10 In the case of the construction shown in Figure 6, in the transverse members 84 connecting the side members 85 and arranged at suitably spaced intervals adjacent to the periphery thereof there are provided races, 86, 87, 88 accommodating a plurality of balls 89, 90, 91 which provide a substantially frictionless support, generally as do the rollers in the constructions illustrated in Figures 3 to 5, for the bundle of wires indicated by the reference 92, thus permitting the 15 bundle as it is drawn forward to rotate about its axis.

Having now described my invention, what I claim as new and desire to secure by Letters Patent is:—

25 1. A machine for twisting together a plurality of wire elements to form ropes or strands comprising a flyer adapted to rotate about a longitudinal axis, winding mechanism for the twisted elements floatingly arranged in the flyer, means 30 for rotating the flyer, guiding means on the flyer and rotatable therewith adapted to direct the bundle of elements to be spun from the axis toward the periphery of the flyer and adjacent to the end of the flyer remote from that at which 35 the said guiding means is arranged further guiding means adapted to cause the elements as a bundle to travel lengthwise of the flyer and to be returned towards the axis thereof and thence to the winding mechanism, said guiding means 40 including a carrier and a plurality of bodies mounted on the carrier to rotate about axes parallel with the axis of the bundle in order to permit substantially free twisting motion of the bundle throughout its travel from the first-mentioned guiding means to the point at which it is 45 returned to the axis of the flyer.

2. A machine for twisting together a plurality of wire elements to form ropes or strands comprising a flyer adapted to rotate about a longitudinal axis, winding mechanism for the twisted elements floatingly arranged in the flyer, means for rotating the flyer, guiding means on the flyer and rotatable therewith adapted to direct the bundle of elements to be spun from the axis toward the periphery of the flyer and adjacent to the end of the flyer remote from that at which the said guiding means is arranged a pulley of a diameter equal to the distance between the axis of rotation of the flyer and the farthest point 50 from the said axis reached by the bundle of wires in its passage from one end to the opposite end of the flyer and a plurality of sets of rolling bodies arranged adjacent to the periphery of the pulley adapted to rotate therewith and, in addition, to rotate about axes at right-angles to the axis of rotation of the pulley.

3. A machine for twisting together a plurality of wire elements to form ropes or strands comprising a flyer adapted to rotate about a longitudinal axis, winding mechanism for the twisted elements floatingly arranged in the flyer, means for rotating the flyer, guiding means on the flyer and rotatable therewith adapted to direct the bundle of elements to be spun from the axis toward the periphery of the flyer and ad-

jacent to the end of the flyer remote from that at which the said guiding means is arranged a pulley of a diameter equal to the distance between the axis of rotation of the flyer and the farthest point from the said axis reached by the bundle of wires in its passage from one end to the opposite end of the flyer, said pulley consisting of two discs forming side members, bridge pieces connecting the discs arranged at intervals adjacent to the periphery thereof and a plurality of rollers mounted in said bridge pieces to rotate about axes at right-angles to the axis of rotation of the pulley and providing in effect a groove in which the bundle of wires will be guided. 5

4. A machine for twisting together a plurality of wire elements to form ropes or strands comprising a flyer adapted to rotate about a longitudinal axis, winding mechanism for the twisted elements floatingly arranged in the flyer, means 10 for rotating the flyer, guiding means on the flyer and rotatable therewith adapted to direct the bundle of elements to be spun from the axis toward the periphery of the flyer and adjacent to the end of the flyer remote from that at which 15 the said guiding means is arranged further guiding means adapted to cause the elements as a bundle to travel lengthwise of the flyer and to be returned towards the axis thereof and thence to the winding mechanism, said guiding means 20 including a carrier and a plurality of bodies mounted on the carrier to rotate about axes parallel with the axis of the bundle in order to permit substantially free twisting motion of the bundle throughout its travel from the first-mentioned 25 guiding means to the point at which it is returned to the axis of the flyer.

5. A machine for twisting together a plurality of wire elements to form ropes or strands comprising a flyer adapted to rotate about a longitudinal axis, winding mechanism for the twisted elements floatingly arranged in the flyer, means for rotating the flyer, guiding means on the flyer and rotatable therewith adapted to direct the bundle of elements to be spun from the axis 30 toward the periphery of the flyer and adjacent to the end of the flyer remote from that at which 35 the said guiding means is arranged a pulley of a diameter equal to the distance between the axis of rotation of the flyer and the farthest point from the said axis reached by the bundle of wires in its passage from one end to the opposite end of the flyer and a plurality of sets of 40 rolling bodies arranged adjacent to the periphery of the pulley adapted to rotate therewith and, in addition, to rotate about axes at right-angles to the axis of rotation of the pulley.

6. A machine for twisting together a plurality of wire elements to form ropes or strands comprising a flyer adapted to rotate about a longitudinal axis, winding mechanism for the twisted elements floatingly arranged in the flyer, means for rotating the flyer, guiding means on the flyer and rotatable therewith adapted to direct the bundle of elements to be spun from the axis 45 toward the periphery of the flyer, said guiding means comprising a plurality of rollers mounted to rotate about axes parallel with the axis of the portion of the bundle of elements with which 50 they are in contact, and adjacent to the end of the flyer remote from that at which the said guiding means is arranged a pulley of a diameter equal to the distance between the axis of rotation of the flyer and the farthest point from 55

the said axis reached by the bundle of wires in its passage from one end to the opposite end of the flyer and a plurality of sets of rolling bodies arranged adjacent to the periphery of the 5 pulley adapted to rotate therewith and, in addition, to rotate about axes at right-angles to the axis of rotation of the pulley.

7. A machine for twisting together a plurality of wire elements to form ropes or strands comprising a flyer adapted to rotate about a longitudinal axis, winding mechanism for the twisted elements floatingly arranged in the flyer, means for rotating the flyer, pulley on the flyer and rotatable therewith adapted to direct the bundle 10 of elements to be spun from the axis toward the periphery of the flyer, said pulley consisting of side members, bridge pieces connecting the said members arranged at intervals adjacent to the periphery thereof and rolling bodies mounted on 15 the bridge pieces and adapted to rotate about axes at right-angles to the axis of rotation of the pulley, and adjacent to the end of the flyer remote from that at which the said guiding means is arranged a pulley of a diameter equal 20 to the distance between the axis of rotation of the flyer and the farthest point from the said axis reached by the bundle of wires in its passage from one end to the opposite end of the 25 flyer and a plurality of sets of rolling bodies arranged adjacent to the periphery of the pulley 30 adapted to rotate therewith and, in addition,

to rotate about axes at right-angles to the axis of rotation of the pulley.

8. A machine for twisting together a plurality of wire elements to form ropes or strands comprising a flyer adapted to rotate about a longitudinal axis, winding mechanism for the twisted elements floatingly arranged in the flyer, means for rotating the flyer, a pulley on the flyer and rotatable therewith adapted to direct the bundle of elements to be spun from the axis toward the 10 periphery of the flyer, said pulley consisting of side members, bridge pieces connecting the side members arranged at intervals adjacent to the periphery thereof, rolling bodies mounted on the bridge pieces and adapted to rotate about axes 15 at right-angles to the axis of rotation of the pulley and adjacent to the end of the flyer remote from that at which the said pulley is arranged a further pulley of a diameter equal to the distance between the axis of rotation of the 20 flyer and the farthest point from the said axis reached by the bundle of wires in its passage from one end to the opposite end of the flyer, said further pulley consisting of two discs forming side members, bridge pieces connecting the 25 discs arranged at intervals adjacent to the periphery thereof and a plurality of rollers mounted in said bridge pieces to rotate about axes at right-angles to the axis of rotation of the said pulley and providing in effect a groove in 30 which the bundle of wires will be guided.

ANTON KRAFT.
